BOTTLE LABEL PRESS

Filed Jan. 11, 1924

Inventor
Edward E. Kallenbach
By his Atty *J. H. Richards*

UNITED STATES PATENT OFFICE.

EDWARD E. KALLENBACH, OF NEW YORK, N. Y.

BOTTLE-LABEL PRESS.

Application filed January 11, 1924. Serial No. 685,591.

To all whom it may concern:

Be it known that I, EDWARD E. KALLENBACH, a citizen of the United States of America, residing in New York, in the country and State of New York, have invented 5 certain new and useful Improvements in Bottle-Label Presses, of which the following is a specification.

This invention relates to bottle label presses generally, and particularly to presses used for securing labels and the like having artistic, raised or embossed formations thereon upon bottles such as perfume bottles and the like.

15 Considerable difficulty has heretofore been encountered in properly attaching labels, especially artistic labels upon bottles with any degree of despatch. On account of the thickness of certain labels, and the rigidity and 20 irregular surfaces thereof, it has been found necessary to hold the labels in place for a considerable period of time before the adhesive substance may have sufficiently set so as properly to hold the label on the bottle.

25 In order so to hold the label in place that the adhesive substance may have time to set, and at the same time relieve the operator so that he may proceed with other work, as 30 for instance, with successively positioning other labels to be secured in place, presses have been contrived. One form of such bottle label presses contemplates the use of a rotatable platform having a plurality of radially extending jaws in which the bottles 35 are placed after the labels are secured thereto, and the jaws then caused to close and hold the label in place on the bottle, and the rotatable platform then successively rotated to facilitate the insertion of other bottles by 40 the attendant. The present invention relates particularly to the type of bottle label presses having such rotatable platforms provided with radially extending bottle receiving jaws.

45 Among the objects of the present invention, it is aimed to provide a bottle label press in which, after a label has been disposed on a bottle, the bottle may be positioned in one of the jaws of the rotatable 50 platform whereupon the rotatable platform in the course of its rotation will cause such jaw automatically to close and hold the label securely in place until it is moved around to the discharge end of the machine, there 55 to be discharged.

Another object of the present invention is aimed to provide a bottle label press having a rotatable platform and radially extending jaws adapted automatically to close and hold the label in place on the bottle, and 60 means for automatically discharging the bottle when the jaws are permitted to release the bottle.

Still another object of the present invention contemplates the provision of a machine 65 having means for automatically securing a label in place on a bottle, and so holding the same for a period of time until the adhesive substance has had time to set, and then discharging the bottle with the thereto attached 70 label so secured in place.

A still further object of the invention is to provide a bottle label press having means for successively causing bottle receiving 75 mouths or jaws to be advanced into bottle receiving position, means for adjusting the speed of this advance to accord with the agility of the operator, means for automatically causing the bottle receiving jaws to close upon the bottle and thereby to secure 80 the labels in place, holding said labels in such clamped position for a period sufficient to permit the adhesive substance to set, then permitting the bottle receiving jaws to open, and causing the bottles to be discharged. 85

The present improvements also contemplate the provision of inclined chutes for receiving the discharged bottles, and the provision of bars cooperating with the inclined chutes to receive and discharge the bottles 90 upon the inclined chutes.

These and other features, capabilities and advantages of the invention will appear in the subjoined, detail description thereof, illustrated in the accompanying drawings in 95 which

Figure 1 is a plan of the same; and

Fig. 2 is a section of the same.

In the embodiment illustrated there is provided a fixed base 1, having secured thereto a central shaft receiving boss 2 and a lateral shaft receiving boss 3. In the boss 2 there is fixed the shaft 4 on which is mounted the bushing 5 which serves as a thrust bearing for the gear 6 also mounted on the shaft 4. 100 The gear 6 meshes with the pinion 7 secured to the gear 8 which pinion 7 and gear 8 are both mounted on the shaft 9 fixed in the shaft receiving boss 3. The gear 8 serves 105 as a driving gear meshing with the worm 110

10 of the motor shaft 11 driven by the motor 12 suitably mounted on the base 1.

The gear 6 is suitably connected to the rotatable platform 13, as for instance, by the 5 screws 14, and is also rotatably mounted on the fixed shaft 4. The rotatable platform 13 is preferably a circular disk and is provided with a plurality of radially extending jaw members 15, the jaws of which extend 10 beyond the periphery of the platform 13, to facilitate the insertion therein of bottles to be treated according to the objects of the present invention.

The jaw members each preferably consist 15 of a rearwardly extending arm 16 which is secured to the disk 13 by any suitable means such as the rivet 17 and has a vertically extending wall 18 at the outer end of said arm 16 which extends a short distance below the 20 arm 16, and there continues into the lower horizontally extending jaw portion 19, and extends above said arm 16 a greater distance, continuing into the upper horizontally extending jaw portion 20. The jaw 25 portion 20 has an enlargement 21 extending upwardly therefrom in which there is formed a pin receiving opening 22. For reinforcing the jaw member, it is preferably provided with the rib 23 extending 30 from the enlargement 21 along the wall 18 and arm 16. The inner surfaces of the jaw portions 19 and 20 are preferably plane and parallel as illustrated. On the lower jaw portion 19, there is preferably secured 35 a cushion member 24 preferably composed of rubber or the like. In the opening 22 there is slidably mounted the pin 25 which has secured to its lower end extending beyond the lower plane surface of the jaw 40 portion 20 a plate 26, to the lower surface of which there is secured a cushioning member 27 similar to the cushioning member 24. The inner or lower face of the cushioning member 27 forms the pressure face to engage 45 the labeled surface of a bottle.

The upper end of the pin 25 is provided 50 with a head 28 between which and the enlargement 21 there is provided a coil spring 29, for resiliently retaining the plate 26 and cushion 27 in raised position against the upper jaw portion 20. The peripheral edge of the head 28 is chamfered at 42 to form a cam surface to facilitate guiding the head 28 under the cam guide 30. The cam guide 55 30 is an arcuate member disposed concentric to the platform 13 and secured in place by the T-shaped frame 31, which is spaced from and supported in place by the standards 32, 33 and 34. The arcuate member 30 has a beveled inclined receiving mouth 35 at the receiving end of the cam 30 in order 60 to cooperate with the chamfered edge 42 of the head 28, and depress the head as it is actuated to travel under, and in contact 65 with the cam 30. The arcuate member as

illustrated is preferably so positioned that the receiving end 35 will be disposed just to the right of the attendant, or to the right of the position where the bottles and the like are inserted into the jaws, and the other end 70 of the arcuate member 30 terminates adjacent to the discharge chute 36 of the device, and before passing over thereto. The discharge end of the arcuate member 30 is also inclined as shown at 37 in order to permit 75 the gradual rise of the head 28 and thereby the gradual release of the bottle engaged between the cushion members 24 and 27.

From the foregoing, it will be seen that 80 after labels are secured to the bottles A, such bottles may be inserted between the cushion members 24 and 27 with the label preferably facing upwardly to engage the upper cushion member 27 and with the heads of the bottles protruding beyond the edges of the 85 jaws as illustrated in Fig. 2. This insertion may take place just to the left of the receiving end 35 of the arcuate member 30. As the rotatable platform is then gradually rotated in the direction of the receiving end 35, the head 28 will come into engagement with the receiving end 35 of the arcuate member 30, and thereupon be depressed, in turn securely 90 to engage the bottle between the cushion members 24 and 27, with the label securely 95 pressed against the bottle by the cushion member 27. As the platform 13 is thereupon gradually rotated, the bottle and label will be so clamped between the cushion members 24 and 27 during the entire period that 100 the jaw member passes under the arcuate member 30 and until it arrives at the discharge end 37 of the arcuate member.

The speed of the platform 13 will be 105 timed to correspond to the agility of the operator, and the length of the arcuate member, dependent upon the agility of the average operator, will be determined so that the period of time required for a jaw member to pass under the arcuate member 30 will 110 correspond substantially to the period of time required for the adhesive substance of a label to set when secured to a glass bottle or the like.

The chute 36 consists essentially of an 115 enclosed rectangular member, inclined, with its supporting platform extending substantially from the level of the lower jaw member 19 to the belt conveyor 43, traveling 120 under the machine as illustrated, and past the discharge end or lower end of the chute 36. To cause the automatic discharge of the bottles from the rotary platform after 125 the same have been released from engagement with the upper jaw portion after the jaw member has passed the discharge end 37 of the arcuate member 30, there is provided the deflector 38 consisting essentially of a strip or bar of metal secured by the post 39 to the platform 1, and having an inclined 130

deflecting tongue 40, extending into the path of movement of the bottles after they have been released from the upper jaw portion as illustrated in Fig. 1, and when such 5 bottle and the jaw member carrying the same is moved directly in front of the receiving end or opening 41 of the chute 36.

It is obvious that various changes and 10 modifications may be made to the details of construction without departing from the general spirit of the invention, as set forth in the appended claims.

I claim:

1. In a bottle label press, the combination 15 with a plurality of radially extending supports for carrying bottles provided with labels, driving means for rotating said supports in a horizontal plane about a common axis, pressure faces travelling with said 20 supports and disposed above said supports, a cam stationary relative to said supports and disposed directly above the path of movement of said pressure faces in order to act in a straight line for causing the 25 said pressure faces to be mechanically and positively lowered into engagement with the labeled surfaces of the bottles during a portion of their rotation, and springs for raising the pressure surfaces out of pressure 30 exerting position and for normally maintaining said pressure faces in position to permit a bottle to be discharged, to receive a succeeding bottle and thereupon again to be actuated by said cam.

35 2. In a bottle label press, the combination with a plurality of radially extending arms having two fixed jaws, the lower jaws forming supports for bottles to be labelled, driving means for rotating said supports in 40 a horizontal plane about a common axis, pressure faces operatively connected to the upper jaws to slide in a vertical direction into and out of engagement with the labelled surfaces of the bottles, springs for normally 45 maintaining said pressure faces out of pressure exerting position, and means for temporarily depressing and anchoring said pressure faces into engagement with the labeled surfaces of the bottles.

50 3. In a bottle label press, the combination with a plurality of radially extending supports for carrying the bottles provided with labels, means for rotating said supports about a common axis, pressure faces 55 travelling with said supports and disposed above said supports normally out of engagement with the bottles, a cam stationary relative to said pressure faces for causing the said pressure faces to be actuated into engagement with the labeled surfaces of the bottles during a portion of their rotation, and a deflector stationary relative to said supports and extending into the path of movement of said bottles when carried by 60 said supports to cause said bottles to be 65

discharged after being released from engagement with said pressure faces.

4. In a bottle label press, the combination 70 with a rotary platform, of a plurality of radially extending jaws on said rotary platform for carrying bottles provided with labels, disks in said jaws for engaging and exercising pressure on the labeled surfaces of the bottles supported in said jaws, means for resiliently anchoring said disks in raised 75 position out of contact with said bottles, and an arcuate cam member for causing said disks to be depressed into engagement with said bottles for a pre-determined period of time.

80 5. In a bottle label press, the combination with a rotary platform, of a plurality of radially extending jaws on said rotary platform for carrying bottles provided with labels, disks in said jaws for engaging and 85 exercising pressure on the labeled surfaces of the bottles supported in said jaws, means for resiliently anchoring said disks in raised position out of contact with said bottles, an arcuate member extending over a part 90 of the path of movement of said jaws, and means engaged by said arcuate member to cause said disks to be depressed into engagement with said bottles for a pre-determined period of time.

95 6. In a bottle label press, the combination 100 with a rotary platform, of a plurality of radially extending jaws on said rotary platform for carrying bottles provided with labels, pressure faces on said jaws adapted to engage the labeled surfaces of the bottles, plungers associated with said pressure faces, resilient means on said plungers to maintain the same at inoperative position, and a cam member cooperating with said 105 plungers to cause said pressure faces to be brought into engagement with said bottles for a pre-determined period of time, said plunger being released after the said period of time by the resilient pressure means attached thereto.

110 7. In a bottle label press, the combination 115 with a rotary platform, of a plurality of radially extending jaws on said rotary platform for carrying the bottles provided with labels, pressure faces on said jaws adapted to engage the labeled surfaces of the bottles, plungers associated with said pressure faces, heads on said plungers, springs on said plungers for resiliently maintaining said 120 pressure faces in releasing position out of engagement with said bottles, and arcuate cam member extending over a part of the path of movement of said heads and depressing the heads engaging therewith.

125 8. In a bottle label press, the combination 120 with a movable platform, of a plurality of jaws on said platform for carrying bottles provided with labels, movable pressure faces in said jaws adapted to engage the la-

beled surfaces of the bottles, a cam member independent of said pressure faces and extending over a part of the path of movement of said jaws, and means attached to 5 said pressure faces and engaged by said cam member to cause said pressure faces to be depressed into engagement with said bottles for a pre-determined priod of time.

9. In a bottle label press, the combination 10 with a platform, of a plurality of supports on said platform for carrying bottles provided with labels, a cam member, pressure faces associated with said supports and adapted to engage the labeled surfaces of 15 bottles, plungers associated with said pressure faces and cooperating with said cam member to cause said pressure faces to engage the labeled surfaces of the bottles for a pre-determined period of time, and means 20 cooperating with said platform to discharge the bottles after they have been subjected to pressure by said pressure faces.

10. In a bottle label press, the combination 25 with a platform, a plurality of supports on said platform for carrying bottles provided with labels, pressure faces, a cam member, means cooperating with said cam member to cause the pressure faces to engage the labeled surfaces of the bottle for 30 a pre-determined period of time, and discharge means cooperating with the platform at the end of the cam member to discharge the bottles from the supports.

11. In a bottle label press, the combination 35 with a platform, a plurality of supports on said platform for carrying bottles provided with labels, a cam member extending over a part of the path of movement of said platform, pressure faces, plungers cooperating 40 with said cam member to cause the pressure faces to engage the labeled surfaces of the bottles when the plungers are engaged by said cam member, and tension means for automatically retracting the plungers and 45 therewith the pressure faces when they are disengaged from said cam member.

12. In a bottle label press, the combination 50 with a platform, a plurality of supports on said platform for carrying bottles provided with labels, a cam member extending over a part of the path of movement of said platform, pressure faces, plungers cooperating 55 with said cam member to cause the pressure faces to engage the labeled surfaces of the bottles when the plungers are engaged by said cam member, means for retracting the plungers and therewith the pressure faces when they are disengaged from said cam member, and a deflector extending into the 60 path of movement of the bottles to discharge the same as they are released from engagement with the pressure faces.

13. In a bottle label press, the combination 65 with a platform, a plurality of supports on said platform for carrying bottles provided

with labels, a cam member extending over a part of the path of movement of said platform, pressure faces, plungers cooperating with said cam member to cause the pressure faces to engage the labeled surfaces of the 70 bottles when the plungers are engaged by said cam member, means for retracting the plungers and therewith the pressure faces when they are disengaged from said cam member, a deflector extending into the path 75 of movement of the bottles to discharge the same as they are released from engagement with the pressure faces, a belt conveyor, and a chute for receiving the bottles when they are discharged by said deflector to feed them 80 to said belt conveyor.

14. In a bottle label press, the combination 85 with a rotatable platform, of a plurality of jaws supported on said platform for carrying bottles provided with labels, cushion members in said jaws, an arcuate cam member extending over a part of the path of movement of said jaws, plungers cooperating 90 with said cam member to cause said cushion members to exercise pressure on the labeled surfaces of the bottles carried by said jaws, springs for retracting the plungers and therewith the cushion members when the cam member disengages said plungers, and a deflecting bar extending into the path of movement of the bottles to dislodge and discharge the same when the cushion meimbers have been withdrawn out of engagement 95 with the labeled surfaces.

15. In a bottle label press, the combination 100 with a rotatable platform, of a vertical shaft on which said platform is rotatably mounted, means for rotating said platform on said vertical shaft, a plurality of jaws disposed at the periphery of said rotatable platform, cushion members in said jaws, plungers vertically slidale in said jaws and secured to said cushion members, heads on said plungers extending above said jaws, an arcuate cam member extending over a part of the 105 path of movement of said heads and cooperating with said heads to cause said cushion members to be pressed into engagement with the labeled surfaces of the bottles carried by the jaws, and tapered ends on said cam member and chamfered edges on said heads to facilitate the smooth initial engagement 110 of said plungers by said cam member and the gradual release of the heads by said cam member.

16. In a bottle label press, the combination 115 with a rotatable platform, of jaws disposed at the periphery of said platform, lower fixed cushion members in said jaws to carry the bottles provided with labels, movable cushion members in said jaws, plungers in said jaws secured to said movable cushion members, and an arcuate cam member extending over a part of the path of movement 120 of said plungers and adapted to engage the 125

same and cause the movable cushion members to exercise pressure on the labeled surfaces of the bottles.

17. In a bottle label press, the combination with a rotatable platform, of jaws disposed at the periphery of said platform, lower fixed cushion members in said jaws to carry the bottles provided with labels, movable cushion members in said jaws, plungers in said jaws secured to said movable cushion members, an arcuate cam member extending over a part of the path of movement of said plungers and adapted to engage the same and cause the movable cushion members to exercise pressure on the labeled surfaces of the bottles, and springs for retracting the plungers and therewith the movable cushion members when the plungers are disengaged from the cam member.
18. In a bottle label press, the combination with a rotatable platform, of jaws disposed at the periphery of said platform, lower fixed cushion members in said jaws to carry the bottles provided with labels, movable cushion members in said jaws, plungers in said jaws secured to said movable cushion members, an arcuate cam member extending

over a part of the path of movement of said plungers and adapted to engage the same and cause the movable cushion members to exercise pressure on the labeled surfaces of the bottles, springs for retracting the plungers and therewith the movable cushion members when the plungers are disengaged from the cam member, and a deflector extending into the path of movement of the bottles to dislodge and discharge the same when the cushion members are caused to withdraw out of engagement therewith.

19. In a bottle label press, the combination with a rotatable platform, of jaws disposed on the periphery of said platform for receiving bottles provided with labels, pressure cushions in said jaws, plungers vertically slidable in said jaws and secured to said pressure cushions, and a cam member fixed relative to the rotatable platform and extending over a part of the path of movement of said plungers and cooperating with said plungers to cause the same to be depressed and therewith to press the cushions into engagement with the bottles.

EDWARD E. KALLENBACH.
